BENDING PRESS FOR TIE-PLATE FLANGES

Application filed April 29, 1925. Serial No. 26,670.

My invention relates to improvements in presses for bending into jaw forming relation the flanges of tie-plate sections of the type comprising a platform member having 5 a perpendicular flange thereon.

A certain tie-plate known as the Barrett tie-plate and rail anchor and disclosed in Letters Patent No. 1,171,581, Feb. 15, 1916, to E. H. Barrett comprises a plate or platform 10 having a jaw thereon for engaging the upper surface of the base of a rail resting on the platform, said platform being apertured to receive spikes for anchoring the tie-plate and for forcing a rail into wedging engagement 15 with said jaw. In one method of forming the Barrett type of tie-plate, apertured sections are struck transversely from a long blank comprising a body plate formed with a perpendicular flange thereon and extending 20 longitudinally of the same. The flange member of such tie-plate section is then bent to turn the outer portion of the flange member into near parallelism with the body plate portion or platform, whereby said flange member 25 is resolved into a jaw for gripping a rail base in a wedging manner.

An object of the present invention is to provide a simple and durable press mechanism for quickly, easily and accurately bending such flanges of such tie-plate sections 30 following the heating of said flanges.

With the foregoing and other objects in view, which will appear in the following description, the invention resides in the novel 35 combination and arrangement of parts and in the details of construction hereinafter described and claimed.

In the drawings, Fig. 1 is an elevational 40 fragmentary view of a press embodying my invention, a portion of the bed of the press being broken away to disclose parts that otherwise would be concealed; Fig. 2 is a vertical sectional view taken on the line 2—2 of Fig. 1; Fig. 3 is a similar view taken on the line 3—3 of Fig. 2; Fig. 4 is a transverse 45 sectional view in detail, the same being taken on the line 4—4 of Fig. 3; Fig. 5 is an elevational view in detail and particularly illustrating the spacing die, and plate ejector both 50 in position different from that shown in Fig.

1; and Fig. 6 is a perspective view of a completed tie-plate and rail anchor.

Referring to the drawings, it will be seen that the illustrated embodiment of my invention includes a frame 10, bed 11 thereon and a ram 12 reciprocable vertically above said bed, all of which parts are common to the ordinary trip-press. Supported on the bed 11 is an anvil structure A comprising a block 13, an anvil frame 14, and a face plate 15. The body of the anvil frame 14 is bolted to the block 13, said frame 14 being formed with a pair of depending arms 14^a, each provided with a lug 14^b which is bolted to the bed 11 of the press. The anvil face plate 15 is supported by and bolted to said anvil frame 14, the working surface of said plate 15 being inclined about thirty degrees from the vertical. Loosely hinged on a bolt 16 passing through the arms 14^a of the anvil frame 14, is an upwardly extended mounting 17 at the upper edge of which is a jaw forming and spacing die member 18. An arm 19 is rigidly fastened at its lower end to the mounting 17, said arm 19 being extended 60 considerably above the anvil structure A. A spring 20, stretched between the arm 19 and the frame 10 of the press acts, through said arm to urge the die member 18 toward the face plate 15. Except in the upper position of the ram 12 there is no opposition to such action of said spring, but when said ram 12 is elevated, a pin 21 thereon engaging a cam-like portion 19^a of the arm 19, holds said arm against the action of said spring 20 with the die member 18 swung away from the face plate 15. The die member 18 being thus disposed, the body plate 22 of a tie-plate section B may be inserted freely between said member 18 and the face plate 15. Placed with the back of said body plate 22 against the anvil face plate 15 the flange 23 of the tie-plate section over-reaches the upper edge of the die member 18 and hangs upon the same. Keyed in the under side of the ram 12 and depending therefrom is a punch block 24, the portions 24^a, 24^b thereof complementing the upper edge 18^a and side 18^b of the spacing or jaw forming die 18. The tripping of the press, which is accomplished in 65 70 75 80 85 90 95 100

the usual manner by conventional means, not shown, results in the downward thrust of the ram 12. In the initial stage of its downward throw, the ram releases the arm 19 (Fig. 1), the pin 21 thereon being at that time out of engagement with the cam-like portion 19^a of said arm. The spring 20 now acting upon the arm 19 pulls it to the right, Fig. 1, thus forcing the spacing die 18 against the body plate 22 of the tie-plate section B and clamping said section against the face plate 15. Continuing downward the punch block 24 strikes the flange 23, which is heated for bending, and turns said flange down into conformity with the spacing die 18, the same spacing the flange with respect to the body plate 22 (Figs. 5 and 6). Returning to elevated position, the ram 12, again acting through the arm 19, swings the die 18 away from the face plate 15 far enough to permit of the removal of the finished tie-plate and the application to the die of a new tie-plate section.

The grip of a bent flange 23 upon the spacing die 18 being at times too strong to permit of the convenient removal of the formed tie-plate through the medium of a pair of tongs, it is desirable to forcibly break the grip between the flange and die and this I accomplish by means now to be described. A bolt 25 reaching through the arms 14^a of the anvil frame 14 provides a pivot for the head of a lever 26 upon which an ejector lug 27 is formed. Said lever 26 reaching downward from the pivot 25, then horizontally therefrom, is stopped at its lowermost lifting limit by engagement with the block 13. At such limit of movement of said lever 26, the ejector lug 27 rests slightly beneath the lower edge of the body plate 22 of a tie-plate section B hanging by its flange 23 on the die 18 (Fig. 1). The free end of the lever 26 slidably engages the edge of a bar 28 hinged to and depending from the ram 12, such engagement being yieldingly maintained by means of a spring 29 stretched between said bar 28 and frame 10 and operating to tilt said bar toward said lever. A catch 29^a on the bar 29 ratchets over a shoulder 26^a on the lever 26 during the downward stroke of the ram 12, but catches beneath said shoulder on the upward stroke of said ram. With said catch 29^a thus hooking under the shoulder 26^a, the lever 26 is swung upward and the ejector lug 27 forced against the body plate 22 of the tie-plate B with the result that the grip of the bent flange 23 on the die 18 is broken and said tie-plate thus freed for removal from the press (Fig. 5). The upward throw of the lever 26 need only be very slight and I provide a simple method of releasing the catch 29^a from the shoulder 26^a on said lever. A finger 26^b depending from the free end of the lever 26 engages the bar 28 upon slight change in the angularity

between said lever and bar, the result being that the bar 28 is pried by the finger 26^b far enough from the lever 26 to release the catch 29^a from engagement with the shoulder 26^a (Fig. 5). Released from the lever 26, the bar 28 continues upward with the ram 12 and the lever 26, weighted sufficiently in opposition to the action of the spring 29, falls back by gravity to its lower limit of movement.

Changes in the specific form of my invention, as herein disclosed, may be made within the scope of what is claimed without departing from the spirit of my invention.

Having described my invention, what I claim as new and desire to protect by Letters Patent is:

1. A press for bending into jaw forming relation the flanges of tie-plate sections of the type comprising a body plate having a perpendicular flange thereon, said press including a frame, an anvil structure thereon, a ram reciprocable vertically thereover, said structure presenting a working surface inclined from the vertical, a mounting hinged at the lower side of the anvil structure, a jaw spacing die carried by said mounting, said die providing a hanger for engagement beneath the flange of a tie-plate section placed with the body plate thereof between said anvil surface and die, an arm rising from said mounting, a spring acting upon said arm, to swing the die against the body plate of a tie-plate section and to clamp the same against the anvil, a projection on the ram, said arm having a cam-like portion adapted to be engaged by said projection on the upward stroke of the ram, whereby the arm is tilted against the action of said spring to swing the die away from said anvil surface, a bending punch on the ram, the same complementing the spacing die and adapted upon the descent of said ram to bend said flange over said die, a lever pivoted on the anvil structure, an ejector lug on said lever for engaging beneath the body plate of a formed tie-plate section, a bar hinged to and depending from the ram, said bar having a catch thereon, a spring acting upon said bar to hold said catch in ratcheting relation with respect to said lever, said catch being adapted to engage and swing said lever, upon the upward throw of the ram, whereby the ejector lug is caused to lift the formed tie-plate section from said die.

2. A press for bending into jaw forming relation the flanges of tie-plate sections of the type comprising a body plate having a perpendicular flange thereon, said press including a frame, an anvil supported thereon, a ram reciprocable vertically above the anvil, the face of said anvil being inclined from the vertical, a hingedly mounted jaw spacing die adjacent said face of said anvil, said die providing a hanger for the flange of a tie-plate section placed with the body plate thereof between

5 said anvil and die, a bending punch on the ram, the same complementing the spacing die and adapted, upon the descent of said ram, to bend said flange over said die, an ejector for lifting a formed tie-plate from said die, means for swinging the die and means for operating the ejector, both of said means being actuated by the ram.

3. A press for bending into jaw forming 10 relation the flanges of tie-plate sections of the type comprising a body plate having a perpendicular flange thereon, said press including a frame, an anvil supported thereon, a ram reciprocable vertically above the anvil, 15 the face of said anvil being inclined from the vertical, a jaw spacing die, a hinged mounting for the die, means for swinging the mounting, said die providing a hanger for the flange of a tie-plate section placed with the body plate 20 thereof between said anvil and die, said mounting swinging means being adapted to clamp the die against the body plate of the section so placed, and a bending punch on the ram, the same complementing the spacer die 25 and adapted, upon the descent of said ram, to bend said flange over said die, and an ejector adapted to engage beneath the formed tieplate section and to lift the same from said die.

30 4. A press for bending into jaw forming relation the flanges of tie-plate sections of the type comprising a body plate having a perpendicular flange thereon, said press including a frame, an anvil supported thereon, a 35 ram reciprocable vertically above the anvil, the face of said anvil being inclined from the vertical, a jaw spacing die, a hinged mounting for the die, means for swinging the mounting, said die providing a hanger for the flange 40 of a tie-plate section placed with the body plate thereof between said anvil and die, said mounting swinging means being adapted to clamp the die against the body plate of the section so placed, and a bending punch on 45 the ram, the same complementing the spacer die and adapted, upon the descent of said ram, to bend said flange over said die.

5. A press for bending into jaw forming 50 relation the flanges of tie-plate sections of the type comprising a body plate having a perpendicular flange thereon, said press including a frame, a reciprocable ram, movably related anvil and die members, the face of the former being inclined from the direction of 55 movement of the ram, the die member providing an abutment for the flange of a tie-plate section placed with the body plate thereof interposed between said members, means for shifting one of said members with respect to 60 the other to bring together the die member and the body plate of the section placed between said members, and a bending punch on the ram complementing the die member and adapted, upon the working thrust of the ram, 65 to bend said flange over said die.

6. A press for bending into jaw forming relation the flanges of tie-plate sections of the type comprising a body plate having a perpendicular flange thereon, said press including a frame, a reciprocable ram, an anvil, 70 the face thereof being inclined from the direction of movement of said ram, a jaw spacing die movably spaced from the face of the anvil and providing an abutment for the flange of a tie-plate section placed with the 75 body plate thereof between said anvil and die, means for shifting the die against the body plate of the section so placed, and a bending punch on the ram complementing the spacer die and adapted, upon the working 80 thrust of said ram, to bend said flange over said die, and an ejector for pushing the formed tie-plate section free from said die.

7. A press for bending the flanges of tie-plate sections, including a frame, a reciprocable ram carried by said frame, an anvil member and a jaw member movable relative to one another and supported on said frame for clamping the body portion of a tie-plate section therebetween, one of said members having a spacing die mounted thereon forming an abutment for the flange of said tie-plate, a bending punch on said ram co-operating with said die for bending the flange of the tie-plate, and an ejector operated by said ram for removing the formed tie-plate from said die. 95

8. A press for bending into jaw forming relation the flanges of tie-plate sections of the type comprising a body plate having a perpendicular flange issuing outwardly from the intermediate portions thereof, said press including a frame, a reciprocable ram, an anvil having the face thereof inclined throughout its extent from the direction of movement of said ram and supporting a tie-plate section 100 for movement along said inclined face, a jaw spacing die spaced from the face of the anvil and having movement at substantially right angles to the inclined face of said anvil, and providing an abutment for arresting the movement of the flange of the tie-plate section placed upon said anvil along the inclined face thereof prior to the engagement of said jaw spacing die with the body of said tie-plate section and for bringing said tie-plate section 105 into final position relative to said anvil, and to so hold the tie-plate section, means for shifting the die against the body of the tie-plate section so placed, and a bending punch in the ram complementing the spacing die for bending the flange of said tie-plate section over said die. 110

9. A press for bending the flanges of tie-plate sections including a frame, a reciprocable ram carried by said frame, an anvil member carried by said frame for supporting a tie-plate section for movement along the face thereof, a jaw member movable at substantially right angles to the face of said anvil and supported on said frame for clamping the 115 120 125 130

body portion of the tie-plate section in final position upon the face of said anvil, one of said members having a spacing die thereon forming an abutment adapted to engage the flange of the tie-plate to arrest the movement thereof along the face of said anvil, and to bring the tie-plate section in final position for bending prior to the engagement of the jaw member with the body thereof, and to so hold the tie-plate section, and a bending punch on said ram cooperating with said die for bending the flange of the tie-plate over said spacing die.

In testimony whereof, I have signed my name to this specification.

MELVIN OVESTRUUD.
